COMBINATION TEETHING RING, COMB, AND
RATTLE

Earl S. Tupper, Smithfield, R. I.

Application October 25, 1956, Serial No. 43,525

Term of patent 14 years

(Cl. D86—8)

Fig. 1

Fig. 2

Fig. 3

Figure 1 is a view in perspective of a combination teething ring, comb, and rattle, embodying my new design;

Figure 2 is a top plan view thereof;

Figure 3 is a front view in elevation thereof; and

Figure 4 is an end view in elevation thereof.

I claim:

The ornamental design for a combination teething ring, comb, and rattle, substantially as shown.
